UNITED STATES PATENT OFFICE.

ADOLPH W. SCHRAMM, OF RIVERTON, NEW JERSEY, AND PERCY RUSSELL, OF BROOKLYN, NEW YORK, ASSIGNORS TO ELECTRO DENTAL MANUFACTURING COMPANY, OF PHILADELPHIA, PENNSYLVANIA, A CORPORATION OF PENNSYLVANIA.

EVACUATOR.

1,094,257.

Specification of Letters Patent. Patented Apr. 21, 1914.

Application filed July 6, 1911. Serial No. 637,152.

To all whom it may concern:

Be it known that we, ADOLPH W. SCHRAMM and PERCY RUSSELL, citizens of the United States, and residents of River-
ton, New Jersey, and Brooklyn, New York, respectively, have invented certain Improvements in Evacuators, of which the following is a specification.

One object of this invention is to provide
10 a device of a relatively simple construction
for rendering a jet of high pressure air
available for the production of a partial vacuum
for drainage of septic matter from
15 anatomical cavities, the device including any
desired form of flexible or stiff nozzle or suc-
tion pipes through which such material may
be drawn, and a container for receiving the
material without danger of dissipation of
the same.

20 Another object of this invention is to pro-
vide a convenient and relatively inexpensive
device for removing or drawing from the
mouth of a patient the dust, waste pieces of
25 filling material and the like, incident upon
dental operations, although its use is by no
means limited to this field; it being es-
pecially desired that the apparatus shall be
of such a nature as to be operated by air
under relatively high pressure.

30 We further desire that the apparatus, con-
structed according to our invention, in addi-
tion to the above noted features, shall in-
clude a container for antiseptic liquid so
35 arranged as to receive the material drawn
away by the device and also to purify the air
exhausted, prior to its escape.

These objects and other advantageous
ends are secured as hereinafter set forth,
reference being had to the accompanying
40 drawings, in which:—

Figure 1, is a side elevation, partly in sec-
tion, illustrating the detail construction of
an evacuator made in accordance with this
invention; Fig. 2, is a plan of the device
45 shown in Fig. 1; Fig. 3, is an enlarged hori-
zontal section on the line *a—a*, Fig. 1; Fig.
4, is an enlarged inverted plan of the remov-
able cap; Figs. 5 and 6 are vertical sections
50 *c—c*, Fig. 3; Figs. 7 and 8 are side eleva-
tions illustrating the detail construction of
a part of the cap; Figs. 9 and 10 are re-
spectively horizontal and vertical sections
of a modified form of the invention, and

Figs. 11 and 12 are side elevations of an- 55
other modification.

In Figs. 1 to 8 inclusive of the above draw-
ings, 1 represents a container, which in the
present instance is in the form of a bottle
whose lower portion is outwardly flared. 60
To the neck of said container is fixed in a
manner to be air tight, an internally thread-
ed sleeve 2 whose upper extremity 3 is pref-
erably of less diameter than its body portion.
To this sleeve or neck piece is removably 65
threaded a cap structure 4 through the cen-
ter of which passes a tube 5—6, whose upper
portion 5 is generally curved so as to be L-
shaped, and it has one end made slightly
tapering in order to removably fit into the 70
correspondingly formed upper end of the
part 6. The other end of said part 5 is
likewise slightly coned or tapered to remov-
ably receive a suitable nozzle piece 7 or a
flexible or other extension, as may be desired. 75
The portion 6 of this tube is permanently
fastened to the cap structure 4, and its lower
part is preferably bent outwardly so as to
be adjacent to and practically parallel with
the outwardly flaring side of the container 80
1, its extremity being bent at right angles so
as to discharge in a line practically tangent
to the generally circular side of the bottle
and at some distance from the center thereof.

Projecting tangentially from the side of 85
the cap structure 4 is a tubular extension 8
for the attachment of a pipe, such as a flexi-
ble hose, leading from a source of relatively
high pressure air, and this extension commu-
nicates with the hollow interior of the cap 90
through a relatively small bore opening 9
which in the present instance is formed in a
separate nozzle piece 10, although it is ob-
vious that it may be formed directly in the
material of the cap structure if desired. 95
The hollow interior of said structure has the
form of a helical passage 11 whose area of
cross section is preferably increased from a
point 12 in line with, but spaced away from,
the minute opening 9 of the nozzle 10, to an 100
outlet opening 13 formed in the under side
of the cap structure, outside of the portion
thereof which is designed to be engaged by
the upper end of the part 3 of the neck piece
or sleeve 2. We preferably place a soft 105
washer or other suitable packing 14 on the
upper portion of the threaded part 15 of the
cap structure so as to form a tight joint with

said bottle. It will be noted that this threaded portion 15 is tubular, the suction pipe 6 passing through it and being spaced away from its inner walls, as indicated at 16, to 5 provide an opening whose upper end communicates through a chamber 17 with the opening 12 in the helical passage 11. With this arrangement of parts, if the tubular extension 8 be connected to a source of high 10 pressure air, a jet of such air will be delivered through the small opening 9 of the nozzle 10 into the part 12 of the helical passage 11, through which it passes to the outlet 13 outside the bottle 1. In flowing through this 15 passage 11, the cross section of the jet of high pressure air increases and its velocity decreases until it reaches a relatively low velocity when it flows out of the opening 13 on the outside of the neck sleeve 2.

20 In passing through the chamber 17 and entering the opening 12 of the passage 11, the jet of high pressure air draws with it the air in said channel as well as that in the annular opening 16 between the pipe 6 and the 25 screw threaded portion 15, and inasmuch as this action is continuous as long as air is discharged from the opening 9, the air within the container 1 is exhausted at a relatively rapid rate. As a consequence, air is continually drawn into the container through 30 the suction pipe 6—5, together with any fluid or small particles of solid material which may be adjacent the nozzle 7 thereof.

Owing to the shape of the container 1 as 35 well as to the disposition of the lower end of the pipe 6, the material drawn in is given a rotary movement within the enlarged portion of said container and remains in said portion, while the air with which it was 40 drawn in is exhausted from the upper part of the bottle without discharging said fluid or solid particles. In some cases an anti-septic liquid may be placed in the container not only to assist in retaining the material 45 entering the same, but also for the purpose of purifying the air before it escapes from said container.

It is of course obvious that nozzles of any desired form adapted for the work to be accomplished may be applied to the upper end 50 of the pipe 5, which may be flexible if desired and of any suitable length. Likewise the size and form of the container 1, may be widely varied without departing from the 55 invention, although when the device is used as a dental evacuator, it preferably has the form above described.

It is to be noted that the container 1 is so formed as to permit the air therein to be exhausted without discharging or carrying with it the fluid or solid particles of material in the lower portion thereof even when the container is tilted and if desired, a removable screen 16^a may be mounted in the 65 container 1, preferably around the pipe 6 so

as to prevent the escape of dust through the opening 16. Further, the jet of high pressure air being directed into a relatively long passage or channel of increasing area or cross section, draws with it in a most efficient manner the low pressure air from the interior of the container, through the opening 16 and chamber 17, while the mixed bodies of high and low pressure air are delivered outside of the container 1 through the discharge opening 13, from which they flow downwardly in such a manner as not to strike the face either of the operator or patient.

70 In the modified form of the invention shown in Figs. 9 and 10, the nozzle piece of the pipe 8 is designed to discharge axially into an outlet pipe 20 preferably forming part of the cap structure 4^a and extending in the same straight line as said pipe 8. As 75 in the case of that form of apparatus shown in the other figures, this nozzle piece is placed away from the opening 12 into the passage 11 of this pipe and the cavity so formed is connected through a passage 16 with the upper part of the container 1. As 80 before, the suction pipe 5—6 passes directly through the cap piece.

85 In order that the air discharged from the device may have but little velocity and flow in such a direction as not to annoy either the operator or the patient, we provide the end 90 of the discharge pipe 20 with a muffler 22 which, while it may be of any desired construction, preferably consists of a hollow, substantially cylindrical structure mounted 95 on the end of said pipe and provided with a series of passages 23 lying around and parallel with the pipe 20 and so connected with the same as to change the direction of flow of air issuing therefrom through 180°, at 100 the same time providing ample space into which such air issuing from the pipe may expand before it is discharged.

105 In that form of our invention shown in Figs 11 and 12 the cap structure 4^b as before is provided with a nozzle piece 8 for connection to a source of high pressure air and this discharges into a passage 11^a curved to change the direction of flow of the air through 180° and of gradually enlarging 110 area of cross section. Adjacent the point of delivery of the nozzle piece 8 in the passage 11^a, is a vertically extending passage 16^b connecting with a strainer tube 25 within the container 1. As before, there is a 115 suction pipe extending through the cap structure 4^b having an outer portion 5^a.

120 Under operating conditions the high pressure air delivered to the nozzle piece 8 is discharged from the large end of the passage 11^a at a relatively low velocity, but in 125 passing from said nozzle piece to this passage, it draws or sucks the air from the container 1^a, thereby inducing an inward flow through the suction pipe 5^a as before de- 130

scribed. It is to be noted in connection with that form of our invention shown in Figs. 1 to 8 inclusive that the suction pipe discharges in a part of the container 1 having a relatively large volume, while the outlet passage 16 opens from the upper part of the said container which is of relatively small volume. As a result, the tendency of the air withdrawn to carry with it the material in the container, is reduced to a minimum.

It is observed that the bottle shown in Fig. 11 is particularly adapted to retain its liquid contents even though it be turned upside down and it is obvious that with this idea in view we may modify the form of the bottle in many ways to obtain the same result, without departing from our invention.

20 We claim:—

1. An evacuator consisting of a container; a structure having a helical passage opening outside said container and connected to the interior thereof; means for delivering a jet of air under pressure into said passage; and a suction pipe connected to the container.

2. An evacuator consisting of a container; a suction pipe for the container; means for producing a vacuum in the container consisting of a structure having a passage of increasing area of cross section connected to the interior of the container; with a nozzle connected to a source of air under pressure and mounted to discharge a jet of said air through said passage.

3. A dental evacuator consisting of a bottle having a suction pipe and provided with an enlarged portion; the end of said pipe terminating within the bottle and being arranged to discharge in a line substantially tangent to the enlarged lower portion thereof; with means for exhausting the air from the upper portion of said bottle.

4. The combination of a container having a suction pipe; a cover for the container, having a passage increasing in area of cross section terminating on its under side and connected to the interior of the container; with means for supplying an air jet to said expanding passage.

5. The combination in an evacuator of a

container having a suction pipe; and means for exhausting the air from the container consisting of a structure mounted thereon having a passage increasing in area of cross section and discharging outside of said container, though connected to the interior thereof; with a nozzle connected to a source of air under pressure in position to deliver a jet of air tangentially to the passage. 60

6. The combination of a container; a cover removably mounted thereon and having a suction pipe; there being two passages in said cover concentric with said suction pipe, one of said passages opening outside of the container and the other passage being connected to the interior of the container and to the inlet of the first passage; with means for discharging a jet of high pressure air into the inlet of the first passage. 70

7. The combination of a closed container; a suction pipe connected to discharge within the same; a structure mounted on the container having a passage therein substantially concentric with the center line of said container and connected to the interior thereof; with means for delivering a jet of air into said passage to exhaust the air from the container, the passage having a downwardly opening outlet placed to discharge 80 air immediately adjacent the sides of the container.

8. The combination of a closed container; a suction pipe mounted to discharge within the same; and means for exhausting the air from the interior of the container, the same including a structure mounted on the container and provided with a relatively elongated passage extending around the axial line thereof and having an air discharge 90 opening placed to deliver the air substantially parallel with and immediately adjacent the sides of the container.

In testimony whereof, we have signed our names to this specification, in the presence 95 of two subscribing witnesses.

ADOLPH W. SCHRAMM.
PERCY RUSSELL.
